UNITED STATES PATENT OFFICE.

ADOLPH TAICHER, OF GREENSTREET, WISCONSIN.

WHEELBARROW.

SPECIFICATION forming part of Letters Patent No. 387,327, dated August 7, 1888.

Application filed March 26, 1888. Serial No. 268,515. (No model.)

To all whom it may concern:

Be it known that I, ADOLPH TAICHER, a citizen of the United States, residing at Greenstreet, in the county of Manitowoc and State 5 of Wisconsin, have invented certain new and useful Improvements in Wheelbarrows; and I do hereby declare the following to be a full, clear, and exact description of the invention, such as will enable others skilled in the art to 10 which it appertains to make and use the same.

This invention relates to wheelbarrows; and it consists in the novel construction and combination of the parts, as hereinafter fully described and claimed, whereby the barrow may 15 be used in winter-time, when the ground is covered with snow, with as much facility as upon ordinary occasions.

In the drawings, Figure 1 is a side view of the barrow for use upon snow-covered ground. 20 Fig. 2 is a plan view of the same from below. Fig. 3 is a side view of the wheel attachment.

A are the two side bars of the barrow, provided with the cross piece B and legs C.

D are the handles. E is the pan or box for 25 the load, and F are cross-braces which unite the cross-piece with the side bars.

G is the wheel, provided with pivots g, projecting from its hub, and a are journals in the ends of the side bars for the pivots to run in. 30

The journals a are downwardly-opening slots, and H are plates pivotally connected to the side bars by the screws h, for covering the open ends of the slots and keeping the wheel-pivots in position. The wheel can be removed as 35 often as desired by slackening the screws and turning the plates, so as to allow the pivots to be removed from the journals.

I is the runner, for use when the ground is covered with snow. This runner is shod with 40 steel at the bottom, and is curved upwardly at each end i, so that the barrow may be moved backward and forward.

J are pivots centrally secured to the upper part of the runner, and j are brackets secured to the cross-piece B for carrying the said pivots. The runner-pivots are substantially 45 under the center of gravity of the barrow when loaded and being pushed along, and very little weight comes upon the arms of the operator, who is therefore able to walk carefully 50 and is not liable to slip up and fall.

The runner can easily be removed and the wheel attached as often as may be desirable.

What I claim is--

1. In a barrow, the combination, with the 55 side bars provided with wheel-pivot journals at their ends and pivoted plates for retaining the pivots in the journals, of the single runner curved upwardly at each end and provided with central pivots projecting laterally from 60 its upper edge, brackets for carrying the runner-pivots, and a cross-piece substantially under the center of gravity of the load for the attachment of the said brackets.

2. In a barrow, the combination, with the 65 side bars and the cross-piece secured to the side bars substantially under the center of gravity of the load, of the single runner curved upwardly at each end and provided with central pivots projecting laterally from its upper edge, 70 and the brackets secured to the said cross-piece for carrying the runner-pivots.

3. The combination, with the frame-work of the barrow, of a single runner curved upwardly at each end and provided with laterally-projecting central pivots supported in the said frame-work substantially under the center of gravity of the load. 75

In testimony whereof I affix my signature in presence of two witnesses.

ADOLPH TAICHER.

Witnesses:

THOMAS TURANEK,
JOSEPH KORINEK.
